UNITED STATES PATENT OFFICE.

JOHN MANOFSKY, OF WARREN, OHIO, ASSIGNOR TO YOUNGSTOWN PRESSED STEEL COMPANY, OF WARREN, OHIO, A CORPORATION OF OHIO.

FEEDING DEVICE.

Application filed November 26, 1923. Serial No. 677,021.

To all whom it may concern:

Be it known that I, JOHN MANOFSKY, a citizen of the United States, residing at Warren, in the county of Trumbull and State of Ohio, have invented a new and useful Improvement in Feeding Devices, of which the following is a specification.

The present invention relates to improvements in feeding devices more particularly in such devices intended for feeding sheet metal blanks to devices for operating thereupon, such as slitters, cutters and the like. The invention will be fully understood from the following description, illustrated by the accompanying drawings, in which a device embodying the invention is shown.

In the drawings,

Figure 1 is a plan view of a device embodying the invention;

Fig. 2 is a vertical sectional view on the line 2—2 of Fig. 1;

Fig. 3 is an enlarged plan view of the feed control device shown on smaller scale at the right hand in Fig. 1;

Fig. 4 is a sectional view on the line 4—4 of Fig. 3;

Fig. 5 is a view in plan of the device shown in Fig. 4 with the upper roll removed;

Figs. 6 and 7 are views in plan of the normally engaging surfaces of the upper and lower rolls respectively of the device of Fig. 4;

Fig. 8 is a vertical section on the line 8—8 of Fig. 4;

Fig. 8^a is a vertical section of rolls 27, 29 in locked position;

Fig. 9 is an end elevation of the device of Fig. 4; and

Fig. 10 is a sectional view on the line 10—10 of Fig. 4.

Referring more particularly to the drawings, the numerals 11, 11 designate parts of the device for operating upon metal blanks, for example, a pair of slitting cutters. They are mounted in a cutter frame 12, which may be suitably constructed for example, as shown in the co-pending application of W. W. Galbreath, Serial No. 613,674, filed January 9, 1923. The blank is fed to the cutters 11 along a feed table 13, and passes through a suitable guide 14 just prior to entering the cutters 11. The feed table 13 may suitably be provided with side rails 15, for guiding the blanks fed therealong.

At a suitable point near the cutters 11, a well or depression 16 is formed in the bed of the feed table 13, and in this is journaled a feed roll 17 which may be driven by any suitable means, for example, the flexible shaft 18. This feed roll 17 is so positioned in the well that its upper surface may engage and act upon the lower surface of a blank fed along the surface of the table 13, such a blank being designated by the numeral 19 on the drawings.

Above the feed roll 17 and co-operating therewith is a feed roll 20, which is journaled in the side members 21^a of a yoke 21 pivotally mounted on a shaft 22 mounted on standards 23 secured to the sides of the feed table 13. The two side members 21^a of the yoke join together to form a projecting member 24 in which is journaled a roller 25, the function and operation of which will be more fully hereinafter described. It will be apparent from the structure already described that upward movement of the yoke members 21 will raise the feed roll 20 out of co-operative relationship with the roll 17 so and the blank fed between the rolls.

In the form of device illustrated, the end of the feed table 13 is carried by a support 26 secured to the cutter frame 12. This support carries the guide 14, and also serves as a mounting for a roll 27, of irregular contour as illustrated more fully in Fig. 8 and hereinafter described. The ends of the roll 27 are suitably formed with journals 28 mounted in the supporting members 26. Above the roll 27 is provided a co-operating roll 29, the ends of which are journaled in arms 30 pivoted on shafts 31. Rolls 27 and 29 are provided with intermeshing gears 32. By reason of the mounting of the upper roll 29 upon the pivotally mounted arms 30, the roll 29 may be moved vertically with respect to the roll 27.

It will be apparent from the foregoing that a blank, as it moves along the feed table, is acted upon by rolls 17 and 20, which feed it along until it encounters the rolls 27 and 29. The rolls 27 and 29 are so constructed that the movement of the blank therebetween raises the upper roll 29 and holds it in raised position until the entire blank has passed therebetween. As herein-after pointed out, the rolls 27 and 29 are also caused to elevate the upper feed rolls 20, thereby preventing further co-operation 110

of this roll with the feed roll 17 in feeding the blanks forwardly, and the roll 29 is also caused to provide a check or stop to forward movement of a second blank during passage of the first blank through the machine.

As shown best in Fig. 8, the surface of the portions of the roll 29 co-operating with the roll 27 are of uneven contour. The greater portion of the operating surface of the roll, designated by the numeral 29^a, is cylindrical. The remainder of the operating surface of the roll is formed by hardened metal inserts 29^b and 29^c, which may suitably be screwed to the body of the roll. The inserts 29^b, which are first engaged by the oncoming blank, are provided with eccentrically depressed portions 29^d, terminating in shoulders 29^e. The inserts 29^c, are provided with eccentric bulges 29^f. The insert 29^b has its surface serrated or knurled, and the entire surface of the roll 29 may also be knurled if desired. The roll 27 has the greater portion of its surface cylindrical, as at 27^a and is provided with hardened metal inserts 27^b, the contour of which follow the cylindrical contour of the surface 27^a. A depression 27^c is formed in the roll 27 opposite the position of the eccentric bulge 29^f on the roll 29. The insert 27^d may be serrated or knurled, and the surface 27^a may likewise be knurled or otherwise roughened, if desired.

The roll 29 is provided, for example, near one end, with a cam portion 34 having a shoulder 35, this cam portion being suitably cut into the body of the roll. A projecting stop member 36 is secured to a support 37 mounted upon the supporting frame 26, and is so positioned as to be slightly above the path of the shoulder 35 when rolls 27 and 29 engage each other. When, however, the roll 29 is raised by the passage of a blank between it and the roll 27, as herein-after described, the cam portion 34 is also raised and the shoulder 35 engages the stop 36 in its movement, and the rotation of the roll 29 is thereby stopped. The roll 29 is provided with a second cam portion 38, formed with a raised portion 39, the cam being suitably cut into the central portion of the roll. The roller 25 of the yoke 21 normally engages this cam.

In operation, a blank 19 is fed along the table 13, and is engaged by the feed rolls 17 and 20 which cause its forward movement toward the cutters 11. As the blank 19 approaches the cutters, it passes into the bite of the rolls 27 and 29, which are in the position shown in Fig. 8. The forward movement of the blank causes the rotation of these rolls, which move together by reason of the intermeshing of the gears 32. As the portion of the roll 29 first engaged (29^d) is eccentrically depressed, the rotation of the roll 29 causes it to be raised, this rising

movement being permitted by the mounting of the roll on the pivoted arms 30. The gears 32 remains in mesh, and the roll 29 continues to rotate. The rise of the roll 29 brings the cam 34 into such position that the shoulder 35 engages the stop 36 at the moment the cam has made a complete revolution. The rolls 27 and 29 are then in the position relative to the blank traveling between them shown in Fig. 8^a, and are held stationary by the impingement of the shoulder 35 on the stop 36. By this time the sheet has reached the cutters 11, which cause its further forward movement. The rolls 27 and 29 remain stationary, the sheet sliding between the insert 27^b of the roll 27 and the insert 29^c of the roll 29. By the movement of the roll 29, the cam 38 has been brought into such position that the yoke 24 is raised, and with it the roll 20. The roll 20 thus becomes inoperative. If a second sheet is fed along the table on top of the blank 19 before the latter has passed entirely to the cutters, the roll 20 is no longer effective to force it forward toward the roll 29. As the end of such a blank moves forward on top of the blank 19, it engages the shoulder 29^e on the roll 29, which is held stationary as long as the blank 19 is passing through. The accidental feed of a second blank to the cutters is thus positively prevented. As soon as the blank 19 has passed entirely through, the upper roll 29 is permitted to drop into the position shown in Fig. 8, and may engage the incoming blank. By this movement the yoke 24 carrying the feed roll 20 is also lowered, the feed rolls 17 and 20 again co-operate and the incoming blank is forced ahead, the operations being repeated with the new blank.

Although the present invention has been described in connection with the specific details of a construction embodying it, it is not intended that these shall be regarded as limitations upon the scope of the invention, except in so far as included in the accompanying claims.

I claim:

1. In combination with means for operating on a sheet metal blank, feeding means for feeding a blank to the operating means, and a pair of cooperating cam rollers operable on entrance of a blank into the operating means for rendering the feeding means inoperative during passage of the blanks therethrough.
2. In combination with means for operating on a blank, feeding means for feeding the blank to the operating means and, means operable on entrance of a blank into the operating means for rendering the feeding means inoperative during passage of blanks therethrough and for checking the passage of a second blank.
3. In feeding and feed control devices.

coacting feed members, and means operable by a blank fed thereby to move said feed members into non-coacting relation.

4. In feeding and feed control devices, a feeding pass, a pair of feed rolls on said feeding pass, one of said rolls being movable relative to the other and means operable by a blank fed between said feed rolls for displacing the movable roll.

5. In feeding and feed control devices, a feeding pass having co-operating feed rolls, one of which is movable with respect to the other, a movable supporting frame for the movable feed roll and a cam roller in the path of a blank fed by said feed rolls, said cam roller being operated by the movement of the blank to move the supporting frame and thereby displace the movable feed roll.

6. In combination with a feeding device, a feed control device comprising a rotatable and vertically movable member engaged by a blank fed by said feeding device, said member being provided with means operable by the vertical movement of said member for rendering the feeding device inoperative during the passage of the first blank.

7. In combination with a blank feeding device, co-operating rolls engaged by a blank fed through said feeding device and rotatable thereby, means for checking the movement of said rolls after a predetermined period of rotation, and stop means provided on one of said rolls for checking the passage of a second blank until the passage of the first blank has been completed.

8. In combination with feeding means for sheet metal blanks, a pair of rotatable rolls in the path of the blanks fed by the feeding device and rotatable thereby, one of said rolls being bodily movable with respect to the other and having an eccentric contour, whereby it is bodily moved during passage of a blank between the rolls, means for stopping the rotation of the rolls during the period of displacement of the movable roll and stop means provided on one of said rolls for checking the passage of a second blank during the passage of the first blank therewith.

9. In combination with a feeding device for feeding metal blanks, a pair of rolls in the path of movement of said blanks, one of said rolls being bodily movable with respect to the other, the bodily movable roll having an eccentric contour and being pro-

vided with a shoulder extending transversely of the pass of movement of the blank, the eccentricity of the movable roll causing it to be displaced during passage of a blank between said rolls, a projecting cam shoulder on the bodily movable roll, a fixed stop positioned to be engaged by the cam shoulder during rotation of the bodily movable roll after its displacement, thereby stopping its rotation when its transverse shoulder is in position to be engaged by a second blank, thereby checking passage of the latter during movement of the first blank through the device.

10. In combination with a feeding device for feeding metal blanks, a pair of rolls in the path of movement of said blanks, one of said rolls being bodily movable with respect to the others, the bodily movable roll having an eccentric contour and being provided with a shoulder extending transversely of the pass of movement of the blank, the eccentricity of the movable roll causing it to be displaced during passage of a blank between said rolls, and means operable on rotation of the bodily movable roll after its displacement to stop its rotation when its transverse shoulder is in position to be engaged by a second blank.

11. In combination with a feeding device for feeding metal blanks, a pair of rolls in the path of movement of said blanks, one of said rolls being bodily movable with respect to the other, the bodily movable roll having an eccentric contour and being provided with a shoulder extending transversely of the pass of movement of the blank, the eccentricity of the movable roll causing it to be displaced during passage of a blank between said rolls, means operable on rotation of the bodily movable roll after its displacement to stop its rotation when its transverse shoulder is in position to be engaged by a second blank, and means operable on rotation of the rolls to stop the operation of the feeding device.

12. In combination with means for operating on a sheet metal blank, feeding rolls for feeding a blank to the operating means, and a pair of cooperating cam rollers operable on entrance of a blank into the operating means for separating said feeding rolls thereby rendering them inoperative during passage of the blanks therethrough.

JOHN MANOFSKY.
